PEDAL FOR VELOCIPEDES

Harry Golden, New York, N.Y., assignor to Ideas for
Auto & Bike Specialties, Inc., New York, N.Y., a cor-
poration of New York

Filed Nov. 29, 1963, Ser. No. 77,604

Term of patent 3½ years

(Cl. D90—14)

FIGURE 1 is a plan view of a pedal for velocipedes embodying my new design;

FIGURE 2 is an outer end elevational view of the pedal;

FIGURE 3 is a side elevational view of the same;

FIGURE 4 is a perspective view of the pedal viewed from the inner end thereof; and

FIGURE 5 is an enlarged vertical sectional view, as seen on the line 5—5 of FIGURE 1, looking in the direction of the arrows.

I claim:

The ornamental design for a pedal for velocipedes, as shown.
